James L. Kimball

UNITED STATES PATENT OFFICE.

JAMES L. KIMBALL, OF SALEM, MASSACHUSETTS, ASSIGNOR TO RUGGLES-KLINGE-MANN MFG. CO., OF SALEM, MASSACHUSETTS, A CORPORATION OF MASSACHUSETTS.

PRESSURE-CONTROL APPARATUS.

Application filed April 19, 1923. Serial No. 633,232.

To all whom it may concern:

Be it known that I, JAMES L. KIMBALL, a citizen of the United States, residing at 9 Dearborn St., Salem, in the county of 5 Essex and State of Massachusetts, have invented certain new and useful Improvements in Pressure-Control Apparatus, of which the following is a specification.

This invention relates to pressure control 10 apparatus in which an electric motor is substituted for the fluid pressure motor, as shown in my application, Serial #574,975, of July 14, 1922.

The purpose of my invention is to provide 15 improved means for controlling dampers, rheostats, and valves or other pressure control devices, so that a predetermined movement of such devices will be effected for a given variation in pressure, and more particularly to provide an improved circuit-interrupting attachment for completely and effectively breaking the circuit at predetermined stopping points regardless of the direction in which the motor is operating.

Another object of my invention is to provide means whereby a motor will operate over a greater or less pressure range according to adjustment between the limit of movement of the particular device which 25 controls, and to provide means adapted to render the motor inoperative at each of a plurality of predetermined cut-off points and provide means whereby the pressure setting is varied at each of said cut-off 30 points.

Oftentimes fluid pressure is not available, or the regulator must be located in a place where it is subject to freezing. In such installations, it is desirable to avoid 40 the use of water under pressure for operating the pressure-actuating device, such as a damper, rheostat or valve.

Compressed air or steam may be available for such purpose, but compressed air or 45 steam is too elastic a fluid to be used for this purpose. A solid fluid body, like water, is required to give a positive movement to the pressure-actuating device and to prevent it from over travelling.

Under such conditions I prefer to use an electric motor and my present invention resides in improved means for controlling the

operation of said motor so as to prevent over travel or hunting action.

The general use of regulators of this class 55 is to control pumps, blowers and dampers, and when used for this purpose, it is desirable to operate such device over as wide a pressure-operating range as possible, in order to prevent hunting action. It is also 60 desirable, in order not to operate the motor continuously, or in small increments of speed regulation, to establish certain fixed cut-off, or non-effective, speed-regulating points, at which the motor will be brought 65 to rest and to maintain its non-effective setting for as great a load or pressure variation as seems desirable, and this feature should be adjustable, to conform to varying 70 load and pressure factors.

It is claimed that if the pressure changes slightly, it is not desirable to change the speed setting for the load and the pressure may return to normal and if they do, a change in speed regulation has been avoided 75 which it was not necessary to make.

While it is desirable to have step action, instead of floating action, in the control of such pressure-regulating devices, it is not desirable to arrange such steps for uniform 80 control, but to arrange such apparatus for variable increments of control to meet any variable factors governing such performance. Take it in the case of the control of a centrifugal pump, such pumps have a 85 variable pumping characteristic, in that no water is pumped until a certain speed is reached. In such cases, it is not desirable to have cut-off or stopping points until the speed of the pump has reached the pumping 90 characteristic of the pump, and for this reason, the motor which controls the speed regulating device should be arranged with a longer operating period between cut-off 95 points while the speed of the pump is being brought up to this point.

It will be seen that if cut-off points were arranged for the first speed-building-up stage, the pump would be unnecessarily operated without effecting any useful result.

After the pump has reached its pumping characteristic, then it should be operated by steps, but such steps should not be uniformly spaced for the reason that the pump-

5 and not uniform action of the pump-controlling means.

Take it in the case of damper control, the first closing movement of the damper used to regulate boiler-furnace draft has very 10 little effect in checking the draft, the final closing movement being the most effective and as uniform variation in steam pressure should produce uniform variation in draft and not uniform variation in damper movement, variable control to compensate for 15 variable factors is found desirable.

These variable factors are found not only in pump and damper control, but also in forced and induced draft fans, they also 20 having a variable blowing characteristic which it is desirable to compensate for by variable action in the controlling means.

In the drawings, Figure 1 shows a vertical elevation of my invention, the pressure chamber and the diaphragm being shown in section. Figure 2 shows the usual connection to a damper for controlling boiler draft. Figure 3 shows the connection to a balanced throttle valve for controlling steam-driven pumps, blowers and other 30 apparatus. Figure 4 shows a connection to a rheostat for the control of motor driven apparatus.

Referring to Figure 1, a pressure chamber 1 has a pipe connection 2 which is operatively connected to the pressure system. A diaphragm 3 is subjected on its underside to the pressure of the system. The pressure on the diaphragm 3 is counterbalanced by weights 4 supported from a lever 5. The lever 5 is pivoted at 6 and engages a pressure cap 7 at a point 8. The lower face of the pressure cap 7 is in contact with the diaphragm 3. The above embodies a preferred pressure-responsive device used for actuating a contact switch for operating a motor 12. A preferred embodiment of a contacting switch is shown mounted on the lever 5, in which 9 is the switch bracket or support. Contact points 10 and 11 are connected in the circuit of the motor 12 by means of a lead wire 13, which is adapted to connect the motor 12 for operation in one direction, and a lead 45 wire 14 that is adapted to connect the motor 12 for operation in the reverse direction. One side of the main-line circuit 15 is connected direct to the motor 12 by means of a lead wire 16, and the other side of 50 the circuit is connected to a double contact point 18 by means of a lead wire 17.

It will be understood that the motor switch shown is only illustrative as in some cases, where a large motor is found necessary, it will no doubt be found desirable

to use a magnetic-contacting switch for stopping, starting and reversing the operation of the motor. The switch operated by the pressure-responsive device described may be used as a pilot switch for controlling the operation of the self-starting magnetic switch.

I shall now describe the operation of the pressure-controlling devices, such as are shown in Figures 2, 3 and 4, from the 75 motor 12. The motor 12 operates a worm 19 which, in turn, operates a worm gear 20, and this gear, in turn, drives a spur gear 21, which engages a gear rack 22. It will be seen that if the motor 12 is operated in the direction indicated by the arrow 23, assuming that the worm 19 is threaded right hand, the gear rack 22 will be operated in an upward direction to close the damper or valve, or to operate the rheostat; and that if the motor is operated in the direction indicated by arrow 24, the 80 rack 22 will be operated in a downward direction to open the damper or the valve, or to operate the rheostat in the reverse 85 direction.

It should be understood that the arrangement for operating these pressure-controlling devices from the motor 12 can be variously arranged and organized without departing from the scope of the invention.

The rack 22 carries a circuit-interrupting attachment 25, which is pivoted to the gear rack 22 at a point 26, and is arranged to be adjusted to a greater or less angle, in relation to the gear rack 22, by means of a slot 27 formed at the upper end of the member 25. A clamping device 28 holds the member 25 at whatever angle is found desirable. An arm 29 is pivoted to a stationary bearing 30. The left-hand end of the arm 29 is connected to the lever 5 by means of a spiral spring 31. The opposite end of the arm 29 carries the double contact points 18. It will be understood that contact points 18, as well as contact points 10 and 11, are properly insulated from the arm 29 and the switch bracket 9. The arm 29 is made fast to a shaft 32, and to the opposite end of the shaft 32 is fastened 110 a roll arm 33, carrying a roll 34, which 115 engages the circuit-interrupting attachment 25.

It will be seen that the spring 31 holds the roll 34 in engagement with the stepped face of the circuit-interrupting attachment 25.

The circuit-interrupting attachment 25 is provided with cut-off blocks 35. While these cut-off blocks are shown uniformly spaced on the member 25, it should be understood that they may be variably arranged, so as to give a much greater travel to the gear rack 22 at the beginning of the stroke than on its final upward movement.

for a given variation in pressure acting on the diaphragm 3.

I shall now explain how the motor is operated in accordance with variations in pressure in the pressure chamber 1. On an increase in pressure in the chamber 1, the lever 5 is raised against the gravity force of the weights 4, which brings the contact point 10 into engagement with the contact point 18, effecting operation of the motor in one direction and when the pressure in the chamber 1 is decreased, the lever 5 is depressed, which brings the contact point 11 into engagement with the contact point 18 and effects operation of the motor in the opposite direction.

I shall now explain how the circuit interrupting attachment breaks the motor circuit at each of the steps 35 located on the member 25. Assuming an increase in pressure in the chamber 1, the contact point 10 will engage the contact point 18, which will effect the operation of the motor in the direction indicated by the arrow 23. This will result in an upward movement of the gear rack 22, and also of the member 25, which is attached to the rack 22. As the member 25 starts to move upward, the next lower step 35 will at first engage the roll 34 to cause the arm 29 to rock slightly about the shaft 32 in a clockwise direction, effecting a firmer engagement of the contact members 10 and 18. As the member 25 continues its upward movement, the spring 31 will cause the roll 34 to snap into place between the said step 35 and the step 35 immediately below it, effecting disengagement of the contact members 10 and 18 and thereby stop the motor. Simultaneously with the snapping into place of the roll 34, the tension upon the spring 31 is released, causing a change in the pressure setting of the pressure device, which means that a new pressure value must be set up before the contact can be again made between the contact members 18 and 10.

On a decrease in pressure in the chamber 1, contact is made between the contact members 18 and 11, which effects operation of the motor in the direction indicated by the arrow 24. This will result in a downward movement of the gear rack 22 and the step member 25, which will place the roll 34 on a higher stepped position, thereby rocking the arm 29 to break the contact between the contact members 18 and 11 to stop the motor; and at the same time, an increased tension is placed on the spring 31 to again change the pressure setting of the pressure-responsive device. As in the case of the upward movement of the member 25, the contact members will be caused to engage more firmly before contact is broken between them.

It should be understood that the cut-off

blocks 35 may be adjusted vertically in relation to one another, so as to effect varying speed regulation of the motor 12 between the cut-off points. These blocks can be so arranged as to effect a certain number of revolutions of the motor between the first and the second cut off points on the first closing movement of a damper or other pressure-controlling device, and to decrease its effective operation a certain number of revolutions between the second and third cut-off points and so on. The cut-off blocks are so spaced as to obtain any number of revolutions of the motor required between the cut-off points.

In accordance with the provisions of the patent statutes, I have illustrated and described the principle of operation of my invention, together with the apparatus which I now consider to represent the best embodiment thereof, but I desire to have it understood that the apparatus shown is only illustrative and is capable of various modifications and that only such limitations shall be imposed as are indicated in the appended claims.

What is claimed is:—

1. In combination with a pressure-controlling device, an electric motor for controlling said device, a pressure-responsive element, and means actuated by said element for effecting the operation of said motor and a circuit-interrupting attachment controlled by the operation of the motor adapted to render the motor inoperative at each of a plurality of predetermined pressure settings of the pressure responsive element and means to adjust said attachment to effect a greater or less pressure variation between the limits of the operation of the pressure-controlling device.

2. In combination with a pressure-controlling device, an electric motor for controlling said device, a pressure-responsive element and a switch operated by said element for effecting the operation of the motor, a circuit-interrupting attachment controlled by the operation of the motor adapted to render the motor inoperative at each of a plurality of predetermined pressure settings of the pressure responsive element and means to adjust said attachment to effect a greater or less pressure variation between the limits of movement of the pressure-controlling device.

3. In combination with a pressure-controlling device, an electric motor for controlling said device, a pressure-responsive element operatively connected to a contact switch for effecting the operation of the motor, and a circuit breaker controlled by the operation of the motor adapted to open said switch at each of a plurality of predetermined pressure settings of the pressure-responsive element and means to adjust said

- 4 circuit breaker to effect a greater or less pressure variation acting on the pressure-responsive element between the limits of movement of the pressure controlling device.
- 5 4. In combination with a pressure-controlling device, an electric motor for controlling said device, a reversing switch having a neutral position in which it is not effective and
- 10 two effective positions for operating the motor in either direction, a pressure-responsive device for actuating said switch to either of its effective positions, a multiple stepped member operated by the motor for returning
- 15 the switch to its neutral position at each stepped position, means to change the pressure setting of the pressure-responsive device simultaneously with the return of the switch to its neutral position, and means to
- 20 adjust the degree of change in pressure setting, or the position of the multiple steps in relation to each other.
5. In combination with a pressure-controlling device, an electric motor for controlling said device, a pressure-responsive element for controlling the motor, a source of electric supply connected with said motor, a switch controlling said supply, means operated by the motor for
- 30 effecting a quick opening of the circuit at predetermined positions of the pressure controlling device, and means for adjusting said circuit breaker as to the duration of travel and the variation in pressure between the
- 35 circuit interrupting points.
6. In a pressure system, a reversible electric motor for controlling the pressure in the system having a range of operation between predetermined limits, means controlled in accordance with the value of the pressure setting of the said pressure for closing the circuit of the motor for operation in one or the opposite direction, means whereby the value of the said pressure setting is varied in accordance with the point in the range of operation of the motor at which the circuit of the motor is closed, and means controlled by the motor for opening the circuit of the motor, thereby to stop the
- 50 motor upon the motor commencing to operate.
7. In a pressure system, an electric motor for controlling the pressure in the system, a movable contact member in circuit with the motor the movement of which is controlled in accordance with the pressure in the system, a contact member in circuit with the motor adapted to be engaged by the first-named contact member to effect a closing of the motor circuit, and means for disengaging the contact members to effect the opening of the motor circuit upon the motor commencing to operate.
- 65 8. In a pressure system, an electric motor for controlling the pressure in the system,
- a movable contact member in circuit with the motor, a scale beam controlled in accordance with the pressure in the system for controlling the movement of the contact member, a contact member in circuit with the motor adapted to be engaged by the first-named contact member to effect a closing of the motor circuit, means for disengaging the contact members to effect the opening of the motor circuit upon the motor commencing to operate, and a spring connection between the second-named contact member and the scale beam.
9. In a pressure system, an electric motor for controlling the pressure in the system, a movable contact member in circuit with the motor the movement of which is controlled in accordance with the pressure in the system, a contact member in circuit with the motor adapted to be engaged by the first-named contact member to effect a closing of the motor circuit, a compensating stepped cam moved by the motor, and means connecting the steps of the cam to the second-named contact member to effect a disengagement of the contact members and an opening of the motor circuit.
10. In a pressure system, a reversible electric motor for controlling the pressure in the system, two movable contact members in circuit with the motor for controlling the operation of the motor in opposite directions, a scale beam controlled in accordance with the pressure in the system for controlling the movement of the contact members in accordance with the pressure of the system, an arm having two contact members in circuit with the motor adapted respectively to be engaged by the scale-beam-controlled contact members to effect a closing of the motor circuit in one or the other direction, and means controlled by the motor for effecting movement of the arm at definite steps in the operation of the motor to separate the arm contact members from the scale-beam-controlled contact members, whereby the motor circuit will be opened and the motor stopped at definite steps in the operation of the motor.
11. In combination, a pressure device, an electric motor for controlling the pressure upon the pressure device, a switch in circuit with the motor having an effective position in which it closes the motor circuit and an ineffective position, means connecting the pressure device to the switch to cause the pressure device to actuate the switch to the effective position to effect a closing of the motor circuit, and a stepped cam moved by the motor for returning the switch to the neutral position.
12. In combination, a pressure device, an electric motor for controlling the pressure upon the pressure device, a movable contact member in circuit with the motor, a

second contact member in circuit with the motor, the pressure device being adapted to actuate the movable contact member into engagement with the second contact member to effect a closing of the motor circuit, a stepped cam moved by the motor, and connections from the stepped cam to the contact members for first causing a firmer engagement of the contact members when the motor commences to operate, and for then effecting an abrupt disengagement of the contact members to open the motor circuit.

reversible electric motor for controlling the pressure upon the pressure device, a switch in circuit with the motor the movement of which is controlled by the pressure device, the said switch having a neutral position in which the motor circuit is open and two closed-circuit positions for controlling the operation of the motor and its direction of rotation, the pressure device being adapted to actuate the switch to the closed-circuit positions, and a stepped cam moved by the motor for returning the switch to its neutral position.

13. In combination, a pressure device, a
